UNITED STATES PATENT OFFICE.

JAMES B. SHEEHY, OF NEW YORK, N. Y., ASSIGNOR OF ONE-THIRD TO
PHILIP C. PECK, OF NEW YORK, N. Y.

INCANDESCENT BURNER.

No. 820,676.

Specification of Letters Patent.

Patented May 15, 1906.

Application filed June 9, 1905. Serial No. 264,380.

To all whom it may concern:

Be it known that I, JAMES B. SHEEHY, a citizen of the United States, and a resident of the borough of Manhattan, city, county, and State of New York, have invented certain new and useful Improvements in Incandescent Burners—as, for instance, those known as the "Welsbach"—of which the following is a specification, reference being had to the accompanying drawings, in which—

Figure 1 is a central vertical sectional view showing my improvement. Fig. 2 is a top view of my improved screen. Fig. 3 is a perspective view of same.

Such mantles are usually heated to incandescence by applying thereto the flame from a Bunsen burner. Experience has demonstrated the desirability of separating such flame from the discharge-orifice of the Bunsen burner by an intermediately disposed and supported screen, usually of wire-gauze, containing a multiplicity of perforations, through which are projected the gases—mingled air and illuminating-gas—issuing from the discharge-orifice of the Bunsen burner. Such screens have heretofore been constructed of either flat or conical or dome-shaped form relatively to the said discharge-orifice and with no means to insure the projection of the major portion of the gas through said perforations in directions substantially at right angles to the sides of the mantle against which said gas impinges, nor to insure such projection of the gas in a plurality of streams of substantially larger diameter than the similar streams by which they are uniformly surrounded.

I have discovered that increased candle-power is imparted to the incandescent mantle and other advantages secured by forming and disposing such screens so as not only to extend over the discharge-orifice of the Bunsen tube in a plane at right angles to the central longitudinal axis of the latter, but also to extend, intermediately of said plane and said discharge-orifice, in an approximately vertically disposed tubular form concentric with said tube and parallel with the proximate walls of said mantle and especially by introducing into said substantially tubular and vertical portions of said screen a plural-

ity of perforations, each very much larger in aperture than the remaining perforations of the mesh of its wire-gauze.

Referring now to the drawings, A is a Bunsen burner, connected, as usual, with gas-pipe B and having centrally-disposed gas-orifice C, air-ports c c, and an annular externally-projecting bead a.

S is a cylindrical sleeve concentric with A, supported thereby and downwardly flared to form a shutter or screen over air-ports c c.

D is a cylinder concentric with S, downwardly constricted to tightly embrace the latter, by which it is thus frictionally supported, and upwardly expanded to form, if desired, a suitable support for sleeve M, which latter carries secured thereto the studs e e, which carry the usual wire frame E, by which the mantle F is supported, as shown, in the usual manner.

The foregoing parts are none of them novel and are described by me only for a better understanding of my invention.

On the mixing-tube of Bunsen burner A, I removably secure a cylinder or tube G, sleeved on latter and supported by its bead a, as shown. The lower part of G fits A closely, as shown. The upper part of G is preferably of slightly greater diameter than A and extends preferably somewhat above the discharge-orifice of the latter, or, if desired, even as much as shown in the drawings; but it will be understood that in all cases G must extend above the lip d of D sufficiently to admit free passage of the gas readily outward from H in a direction at right angles to the central longitudinal axis of the burner.

H is my improved screen composed, preferably, of wire-gauze, fitted to and supported by the edges of the discharge-orifice of G. It will be observed that the gauze H is by my improvement so shaped and located that parts thereof are disposed at a right angle to the central longitudinal axis of the Bunsen burner A and parts thereof cylindrically and concentrically and parallel with A, also that in the last-described portion of said screen are a plurality of perforations h h of much greater aperture than and surrounded equally on all sides by the substantially uniform smaller per-

forations $h' h'$ between the meshes of the gauze.

By reason of the novel form and disposition of my screen H and the elements associated therewith I am enabled to employ, if desired, higher gas-pressure than in the previous constructions, and this without any injurious results, but, on the contrary, with great increase of candle-power. I am also with equal pressures enabled to direct the gases from the Bunsen tube in such relation and comparative volumes to the mantles as to increase the light efficiency and durability of the latter. These results are due in part to the shape and disposition of my screen and its perforations and also in part to the relation of the parts D and G to the outflowing gas, whereby the jets thereof are sheltered from induced upwardly-moving air-currents. I am also by my construction enabled to separate the screen from the mantle for cleaning or other purposes, and this with consequently diminished risk of breaking the mantle. Moreover, my form of construction is readily adapted for application to different styles and sizes of Bunsen burners and also with equal increase of candle-power to the use of smaller mantles than employed in other forms of construction.

In Fig. 1 of the drawings the relative size, proportion, and location of a mantle of the usual proportions and diameter usually required with burner-tubes of the size indicated is shown suggestively merely by the line F; but with my burners, owing to their peculiar construction, a mantle of smaller diameter may be used—that is to say, a diameter such as to admit disposition of its lower portion between the tube G and the cylinder D—in which case the said reduced mantle will be found to give substantially as satisfactory results as the more expensive and fragile mantles of larger diameter, D, as a fender tending to protect its lower portions from injury.

It will be observed that I do not confine myself to the precise construction, form, or disposition of my screen nor to the particular size of major apertures therein, as shown in the drawings. These may all be varied without departing from my invention, one essential and distinguishing characteristic of which consists in the formation and disposition of the screen in its relation to other parts, so that the major portion of the gases from the Bunsen burner shall be projected through the perforations of the screen in directions rectangularly inclined directly against the sides of the mantle where most proximate to such perforations, and another essential and distinguishing characteristic of which is the incorporation in the screen of perforations having very much greater aper-

tures than those of the remaining perforations by which they are on all sides uniformly surrounded and which major perforations are also so located as to project the gases therethrough in streams the central longitudinal axes of which are disposed at a right angle to the most proximate sides of the mantle. By these means the pressure of the gas is not unduly checked by the screen, while at the same time the "popping" back of the flame is prevented.

Having now described my invention, what I claim as new, and desire to secure by Letters Patent, is the following, viz:

1. In an incandescent burner, of the type described, intermediate the discharge-orifice of its Bunsen burner and the sides of its mantle, a screen containing perforations of a given diameter and also interspersed among, and surrounded by, said perforations other perforations of a substantially larger diameter disposed and proportioned to project the gases passing therethrough in streams the central longitudinal axes of which are angularly disposed to that of the burner.

2. In an incandescent burner, of the type described, intermediate the discharge-orifice of its Bunsen burner and the sides of its mantle a screen containing perforations of a given diameter and also, interspersed among and surrounded by said perforations, other perforations of a substantially larger diameter disposed so as to project the gases from said burner horizontally in streams the central longitudinal axes of which are at an angle to the proximate surface of the sides of said mantle.

3. In an incandescent burner the combination of a mantle, a Bunsen burner, an auxiliary tube concentric with and removably secured to said Bunsen burner, disposed over the discharge-orifice of said auxiliary tube a screen containing perforations disposed to project the most part of the gases horizontally in streams the central longitudinal axes of which are at a right angle to the proximate surface of the sides of said mantle, and below said screen and concentric with said tube and said cylinder, another burner of greater diameter, open at the top and closed at the bottom.

4. In an incandescent burner of the type described the combination of a mantle, a Bunsen burner, an auxiliary tube concentric with and removably secured to said Bunsen burner, disposed over the discharge-orifice of said auxiliary tube a screen, and below said screen and concentric with said tube and said burner another cylinder of greater diameter, open at the top, closed at the bottom, and so shaped, supported and disposed relatively to said tube as to admit disposition between them of the lower portion of said man-

tle, said screen containing perforations of a given diameter and also, interspersed among and surrounded by said perforations, other perforations of a substantially larger diameter disposed so as to project the gases from said burner horizontally in streams the central longitudinal axes of which are at an an-

gle to the proximate surface of the sides of said mantle, substantially as described.

JAMES B. SHEEHY.

GEORGE G. MEASURES.

It is hereby certified that in Letters Patent No. 820,676, granted May 15, 1906, upon the application of James B. Sheehy, of New York, N. Y., for an improvement in "Incandescent Burners," errors appear in the printed specification requiring correction, as follows: In line 112, page 2, the word "cylinder" should read *burner*, and same page and line, the word "burner" should read *cylinder*; and that the said Letters Patent should be read with these corrections therein that the same may conform to the record of the case in the Patent Office.

Signed and sealed this 16th day of October, A. D., 1906.

[SEAL.]

F. I. ALLEN,

Commissioner of Patents.
